(57) CLAIM

The ornamental design for a brush head packaging, as shown and described.

DESCRIPTION

FIG. 1 is a front view of the brush head packaging system of the present invention.

FIG. 2 is a bottom elevation view of the present invention.

FIG. 3 is a top elevation of the present invention.

FIG. 4 is a rear view of the present invention.

FIG. 5 is a right side elevation view of the present invention.

FIG. 6 is a left side elevation view of the present invention.

FIG. 7 is a front perspective view of the present invention; and,

FIG. 8 is a rear perspective view of the present invention.

The broken lines illustrate portions of the brush head packaging which form no part of the claimed design.
